SUCTION CLEANER NOZZLE

Edward H. Yonkers, Jr., Glencoe, Ill.

Application March 6, 1946, Serial No. 652,297

5 Claims. (Cl. 15—354)

1

This invention relates to a suction cleaner nozzle and particularly to a nozzle useful on rugs, carpets or the like. The nozzle herein is an improvement upon that disclosed and claimed in my Patent 2,296,077, granted September 15, 1942. Like the patented nozzle, the nozzle herein may be used either with, or without, a brush near the suction opening.

As pointed out in my patent, cleaning of rugs, carpets or textile material by suction involves two extreme conditions which must be provided for. In one condition, deep cleaning requires that air be pulled through the rug or carpet into the suction nozzle, and thus remove deeply-embedded dust or dirt. The other condition involves surface cleaning wherein lint, pieces of paper and the like resting on top of the carpet or rug are to be removed therefrom.

Both types of cleaning involve different operating conditions and, thus, may normally require different suction nozzles. The nozzle disclosed and claimed in the patent previously referred to provides both types of cleaning. Thus, for deep cleaning, it is essential that the nozzle opening be pressed against the carpet surface so that air will be pulled up through the textile material. For surface cleaning, it is essential that the nozzle or portion thereof be raised a short distance above the textile surface to provide a clearance for a surface layer of air. It is essential, however, that this clearance be relatively small so that maximum suction effect may be exerted along the textile surface.

The invention disclosed herein improves upon the nozzle previously patented in that means are provided for maintaining the selected nozzle operating condition. By virtue of the invention herein, the nozzle may operate for deep cleaning when moved in one direction and operate for surface cleaning when moved in the reverse direction, and such operating conditions are maintained in spite of such variables as the height of the operator and manner of holding the actuating handle.

In accordance with the invention, there is provided a spring biased flexible coupling means between two parts of the suction nozzle as a whole whereby the nozzle may adjust itself to a desired operating condition. The nozzle disclosed herein is adapted for use with any cleaner, though par-

2

ticularly adapted for use with the so-called tank type cleaner, wherein the suction-generating and dirt-retaining means are connected to the nozzle through a hollow handle and flexible hose. Thus, the suction nozzle may be used with any of the suction cleaners disclosed and claimed in my Patents 2,198,568, 2,242,277 and 2,242,278.

The features of my invention which are believed to be novel are particularly set forth in the appended claims. The invention itself, however, together with the advantages thereof, may best be understood by reference to the description following herein taken in connection with the accompanying drawings. Figure 1 is a top plan view looking down upon a suction nozzle embodying the invention. Figure 2 is a rear elevation of the suction nozzle of Figure 1. Figure 3 is a side elevation of the nozzle in a deep-cleaning position along line 3—3 of Figure 1. Figure 4 is a side elevation along line 3—3 of Figure 1 of the nozzle in a surface-cleaning position. Figure 5 is a perspective fragmentary showing of the brush and spring biasing means.

Nozzle body 10 has inlet opening 11 bounded by front edge 12, rear edge 13 and sides 14 and 15 respectively. The inlet may have a generally rectangular outline. It will be noted that front edge 12 is rounded to provide a curved bottom surface. The curvature is with reference to a line transverse to the entire nozzle; i. e. generally parallel to edge 12.

Nozzle body 10 may be formed of any suitable metal or plastic and defines air and dirt channel 11 and two collateral air and dirt channels 16 and 17. Nozzle body 10 is so formed as to provide bosses 18 and 19 aligned transversely of the entire nozzle structure and defining channels 16 and 17 respectively. Bosses 18 and 19 are machined or finished to provide hollow trunnion bearings and communicate with the air and dirt passage previously described. Pivottally secured in bosses 18 and 19 is fixture 21. Fixture 21 is hollow and communicates with channels 16 and 17 forming the interior of bosses 18 and 19. Rubber sleeves 22 and 23 may be provided at the joints between fixture 21 and the two bosses to prevent leakage of air. Fixture 21 is provided with pipe coupling 25 forming a discharge for the nozzle. Coupling 25 may have attached thereto the customary hollow handle or hose.

Nozzle body 10 has chamber 27 of the structure which is isolated from the normal air and dirt path within the nozzle. Chamber 27 of the housing has eccentric roller 28 pivotally secured at sides 14 and 15. Eccentric roller 28 carries pin 29 at each end thereof, said pin cooperating with parts 30 and 31 of nozzle sides 14 and 15 to limit roller movement. Roller 28 is designed so that, upon forward movement of the nozzle along a carpet, roller 28 will turn counter-clockwise to one end position, as seen in Figure 3, and drop the nozzle structure around front edge 12. Upon rearward movement of the nozzle, as shown in Figure 4, roller 28 turns clockwise to its other end position and raises the rear portion of the nozzle structure with respect to front edge 12. Eccentric roller 28 is limited to about 180 degrees of travel. As clearly indicated in Figure 4, the rise of the nozzle structure is such as to provide a slight clearance between side 13 and the surface to be cleaned. Thus, air may move along the surface under side 13 into intake region 11.

Roller 28 preferably extends a substantial portion of the width of the entire nozzle and thus provides a large area against which the surface to be cleaned may act. Thus, the function will be great enough to operate the eccentric roller.

It is preferred to provide some spring bias between fixture 21 and the rest of the nozzle structure tending to seat inlet 11 down against the surface to be cleaned. To this end, spring 33 has part 34 rigidly attached to fixture 21. Spring 33 has end 35 bearing against nozzle body 10. Spring 33 is arranged to bias fixture 21 to the position shown in Figure 2. This position may correspond to the lowest possible handle position. Any moving of fixture 21 upwardly away from the floor, as seen in Figures 3 and 4, will result in a firm seating of nozzle edge 12 on the surface to be cleaned. Stop 36 on fixture 21 may be provided to limit the upward travel of fixture 21.

While the suction cleaner nozzle attachment thusfar described may be used with advantageous results, it is preferred to provide a brush. To this end, long straight brush 40 of usual construction may be disposed on rod 41 having bent arms 42 and 43 and pivot tips 44 and 45. As clearly indicated in the drawing, pivot tips 44 and 45 are mounted in the opposing sides 14 and 15 of the nozzle body in chamber 27. The mounting is such that brush 40 extends transversely of the nozzle body in front of eccentric roller 28. Bent stop arm 47 rigidly attached at 48 to the nozzle body is provided to limit the downward movement of brush 40 on its pivots. Spring 49 is provided to bias the brush against stop arm 47 but permitting brush movement upwardly. Brush 40 itself is pivotally mounted on rod 41 and is biased by spring 50 toward eccentric roller 28. Thus, springs 49 and 50 tend to maintain brush 40 in the position shown in Figure 4. Upon forward movement of the nozzle body, eccentric roller 28 drops the nozzle body to the position shown in Figure 3 and the carpet or other surface being cleaned engages the brush tips as shown. The brush is rocked downwardly, and the brush tips are firmly pressed against the surface being cleaned. Upon rearward movement, nozzle edge 13 clears the floor surface. Brush 40 assumes its normal position and clears the floor surface. The clearance of the brush tips may be made as great as desired.

It is evident that the entire structure is simple and foolproof. The nozzle will assume the position shown in Figures 3 and 4 irrespective of

operator variations in height or manner of holding. A spring bias between the fixture and nozzle body urges the body downwardly against the floor during cleaning so that the nozzle positions shown in Figures 3 and 4 are always definitely assumed when the nozzle is moved in the proper directions.

Thus, highly efficient cleaning will result. It will be understood that the nozzle as a whole is normally moved along a line perpendicular to front surface 12, the forward direction being such that edge 12 leads.

What is claimed is:

1. A suction cleaner nozzle comprising a nozzle body having an elongated intake opening transverse to the line of nozzle travel on a floor during cleaning, said opening having edges formed by body portions lying in a flat plane, a long roller eccentrically supported on said nozzle body rearwardly of said inlet and extending transversely for substantially the nozzle width and forming a surface providing a transverse region of support on said floor for said body, means for limiting the rotation of said roller to substantially 180 degrees, said roller and floor cooperating during nozzle movement to raise or lower said nozzle body depending upon the direction of nozzle travel, a fixture having a discharge opening, said fixture being carried by said nozzle body for receiving air from said nozzle body and discharging the same into a suction cleaner and means for mounting said fixture so that it is movable with respect to said nozzle body only in a vertical plane, said fixture having its discharge

30 opening formed to function as part of a pipe coupling for cooperation with a tubular handle to be used by an operator for manipulating said nozzle and said nozzle under normal conditions of use being supported on said floor by said roller and one transverse inlet edge in all positions and being movable by the action of said eccentric roller to pivot said nozzle at all times about said one transverse edge and to move the other transverse edge to or from the floor and maintain said nozzle opening in a position for deep or surface cleaning.

2. The structure according to claim 1 wherein the front edge is always on the floor and wherein a brush is disposed between the roller and rear edge of the opening.

3. A suction cleaner nozzle comprising a nozzle body having an elongated intake opening transverse to the line of nozzle travel on a floor during cleaning, said opening having edges formed by body portions lying in a flat plane, a long roller eccentrically supported on said nozzle body rearwardly of said inlet and extending transversely forming a surface providing a transverse region of support on said floor for said body, means for limiting the rotation of said roller to substantially 180 degrees, said roller and floor cooperating during nozzle movement to raise or lower said nozzle body depending upon the direction of nozzle travel, a fixture having a discharge opening carried by said nozzle body for receiving air from said nozzle body and discharging the same into a suction cleaner, means for mounting said fixture so that it is movable with respect to said nozzle body only in a vertical plane and means for biasing said fixture relative to said nozzle body to urge said fixture toward the floor when said nozzle rests on the floor and from which position said fixture is moved against its bias by an operator during cleaning whereby said nozzle is positioned at all times so that a

transverse edge of the intake opening always engages the floor surface during cleaning irrespective of the height or position of the operator, said nozzle body being tilted with respect to said edge to move the intake opening for surface or deep cleaning respectively when the direction of nozzle travel is changed.

4. The structure according to claim 3 wherein a brush is disposed between the roller and rear edge of the opening.

5. The structure according to claim 3 wherein said eccentric roller is adapted to raise the rear edge of the opening upon forward movement of the nozzle and to drop said rear edge upon backward movement of the nozzle.

Certificate of Correction

Patent No. 2,510,270

June 6, 1950

EDWARD H. YONKERS, JR.

It is hereby certified that errors appear in the printed specification of the above numbered patent requiring correction as follows:

Column 1, line 30, for the words "layer or" read *layer of*; column 3, line 26, for "function" read *friction*;

and that the said Letters Patent should be read with these corrections therein that the same may conform to the record of the case in the Patent Office.

Signed and sealed this 29th day of August, A. D. 1950.
